UNITED STATES PATENT OFFICE.

JACKSON R. UHLER, OF TATAMY, PENNSYLVANIA.

CYLINDRICAL-GLASS-CUTTER HOLDER.

Application filed May 13, 1924. Serial No. 713,073.

To all whom it may concern:

Be it known that I, JACKSON R. UHLER, a citizen of the United States, residing at Tatamy, in the county of Northampton and 5 State of Pennsylvania, have invented certain new and useful Improvements in Cylindrical-Glass-Cutter Holders, of which the following is a specification, reference being had to the accompanying drawings.

10 This invention relates to devices for holding and cutting glass cylinders, such as bottles, tubes and other cylindrical glass objects.

The ordinary way of cutting glass cylinders is by filing a ring around the glass and then suddenly jarring or otherwise giving a shock to the glass and causing it to break where it has been filed. This method, and indeed any other known to me, for commercial purposes is inefficient due to the fact that the glass breaks crookedly and beside this the method requires the manual labor of filing. Thus thousands of dollars worth 20 of cylindrical glassware are thrown away 25 every day because they are not properly cut.

My object is to provide a means for holding a cylinder of glass while it is being cut, and means for cutting the glass comprising a cutting string formed to make one complete turn around the glass, the holder for the glass being so formed as to guide this string and prevent its cutting out of proper position, and being also so formed as to permit the ends of the string to be readily manipulated to oscillate the string and thus frictionally heat up the glass at the point where the string surrounds it. After being sufficiently heated by frictional engagement with the string, the glass is withdrawn and 30 immersed in cold water, which causes the glass to break at the place desired.

A further object is to provide a device of this character which embodies a frame, the frame being contractible so as to bind 45 upon the glass or expandible so as to permit the frame to be used on larger or smaller cylinders, and the frame being formed with perforations through which the cutting cord or heating cord passes, there being a plurality of these perforations so that the cutting member may be used with glass of various diameters.

A still further object is to provide a frame of this character with grooves which engage 50 the cord passing around the glass cylinder and accommodate this cord and at the same

time prevent the cord from being shifted from one side to the other and thus not cutting true.

Other objects will appear in the course of 60 the following description.

My invention is illustrated in the accompanying drawings, wherein:—

Figure 1 is a front elevation of a glass cylinder cutter constructed in accordance 65 with my invention partly in section;

Figure 2 is a top plan view of the construction shown in Figure 1;

Figure 3 is a vertical section on the line 70 3—3 of Figure 1;

Figure 4 is a fragmentary sectional perspective view of the member 17;

Figure 5 is a fragmentary sectional view of the member 12.

Referring to these drawings, it will be seen 75 that the cylinder A of glass, and which may be a glass bottle, a glass tube, a flask, beaker or the like, is held in a frame, which frame holds the glass so firmly that the cylinder cannot rotate or otherwise move. This 80 frame is composed of the side members 10, these side members being preferably formed of channel iron and having a plurality of perforations set very close together and extending longitudinally of the side members, 85 these perforations being designated 11. There are two of these channel-shaped side members, and coacting therewith are the upper and lower clamping members, the lower clamping member 12 being preferably of 90 wood, as shown, and being formed with perforations at its ends adapted to align with the perforations 11 of the side members and be held at any desired height by means of a pin 13 which passes through these 95 perforations 11 and through the clamping member 12. The upper face of this clamping member is grooved, as at 14, the groove extending nearly the entire length of the clamping member. This clamping member 100 is preferably of wood. The upper clamping member 15 is also preferably of wood and has its ends fitting within the channel-shaped end members and is also perforated at its ends for the passage of holding pins 105 16. The under face of this member 15 is formed with a longitudinally extending channel 17 and is also formed with a plurality of cord passages 18 which pass downward through the member 15 from the top to the bottom thereof and open into this groove 17. Coacting with the members is a

100

105

110

cord 19, which in cutting the glass is wrapped one complete turn around the glass and the ends passed out through the proper holes 18.

In the use of this device, the cylinder to be cut is placed within the clamping frame and the upper and lower sections adjusted so as to clamp the cylinder between them, as illustrated, the cord being passed around the glass to form one complete turn, as before stated, and these turns of the cord being disposed within the grooves 14 and 17. The extremities of the cord are passed out through two of the perforations 18. When the glass is securely clamped, the operator takes hold of both ends of the cord and pulls rapidly up and down. This causes friction and heats up the glass, while the upper and lower clamping members with their grooves hold the cord or string at the place of cutting desired. After the glass has been sufficiently heated by the friction of the cord, the glass is withdrawn and immersed in cold water, which causes the glass to break at the point desired.

Without this holder it is impossible to cut large cylindrical glass accurately and I have found in practice that with this holder it takes about sixty seconds to cut cylindrical glass of any diameter and that it is cut accurately at any place desired. By using this method of cutting, the edge of the glass is more uniform and less sharp. This is a valuable item, especially when poor grades of glass are cut, such as common bottles. Thousands of dollars worth of cylindrical glassware are thrown away every day, such as flasks, beakers, graduates and bottles of all kinds. These would be used if they could be satisfactorily cut for other purposes, especially such cylindrical glass as is used in laboratories where the glass is cracked or little pieces broken out. These cannot be fixed and are of no more value unless the broken part is cut from the good part. There is no means of doing this and hence everything is discarded.

I claim:

1. Means for cutting glass cylinders comprising clamping members adapted to clamp the cylinder between them, and a cord adapted to be disposed around the cylinder and oscillated, said clamping members having means for guiding the cord and preventing any movement of the cord out of the plane of cutting.

2. Means for cutting cylindrical glass comprising clamping members adapted to clamp a glass cylinder between them and each formed with longitudinal grooves constituting guides, and a cord adapted to be coiled around the glass and oscillated, one of said clamping members having openings through which the ends of the cord pass.

3. Means for cutting cylindrical glass comprising lateral members, upper and lower clamping members adjustable on said lateral members toward or from each other and adapted to clamp the cylinder of glass between them, said clamping members having longitudinal grooves on their confronting faces and one of said clamping members being formed with a series of apertures opening into said grooves through which the ends of a cord coiled around the glass may pass.

4. Means for cutting glass cylinders comprising lateral members, each having a series of perforations along its entire extent, upper and lower clamping members having sliding engagement with the lateral members and having means passing through said perforations adapted to hold the clamping members in adjusted and clamping position, the upper and lower clamping members each having a longitudinal groove on its inner face, one of said clamping members having a series of openings extending from the exterior of the clamping member into said groove and through which the ends of a cord coiled around the glass may pass.

5. Means for cutting cylindrical glass comprising a clamping frame within which the cylinder of glass is adapted to be clamped and including opposed members engaging the glass, the confronting faces of the opposed members being formed with longitudinal grooves and one of said members having a series of perforations opening into the grooves, and a cord adapted to be coiled around the glass and having its ends passed through said perforations.

6. Means for cutting cylindrical glass comprising lateral members channel-shaped in cross section and formed with a series of perforations, upper and lower members having their ends adapted to be disposed within the channel-shaped lateral members and having perforations adapted to align with any pair of perforations in the lateral members, pins passing through said perforations and holding the clamping members in adjusted position upon the lateral members, the lowermost clamping member having a longitudinally extending groove on its upper face and the uppermost clamping member having a longitudinally extending groove on its lower face and being formed with a series of vertical openings extending from the upper face of said member and opening into said groove, and a cord passing around the glass to be cut and having its ends adapted to extend through any pair of said last named perforations.

In testimony whereof I hereunto affix my signature.

JACKSON R. UHLER.
